CLOSURE CAP FOR BOTTLES OR SIMILAR ARTICLES

Bert W. Nielsen, Fullerton, Calif., assignor to Golden Citrus Juices, Inc., Fullerton, Calif., a corporation of California

Application June 5, 1952, Serial No. 20,057

Term of patent 14 years

(Cl. D58—26)

To all whom it may concern:

Be it known that I, Bert W. Nielsen, a citizen of the United States, residing at Fullerton, county of Orange, State of California, have invented a new, original, and ornamental Design for a Closure Cap for Bottles or Similar Articles, of which the following is a specification, reference being had to the accompanying drawing, forming a part hereof.

Fig. 1 is a top plan view of a closure cap for bottles or similar articles, showing my new design;

Fig. 2 is a side elevational view thereof; and

Fig. 3 is a horizontal cross-sectional view thereof, taken on the line 3—3 of Fig. 1.

I claim:

The ornamental design for a closure cap for bottles or similar articles, as shown.

BERT W. NIELSEN.
